UNITED STATES PATENT OFFICE

2,525,034

NEEDLE THREADER

John N. Jamo, Grand Rapids, Mich.

Application February 17, 1947, Serial No. 729,162.

3 Claims. (Cl. 112—225)

1

The present invention relates to needle threaders and more particularly to a device for threading the needles of sewing machines, and this application is a continuation-in-part of my co-pending application Serial No. 601,506, filed June 25, 1945, now matured into Patent No. 2,476,872, dated July 19, 1949.

The primary objects of the invention are to provide a needle threader having a manually operable plunger for engaging a thread and passing the same through the eye of a needle; to provide such a needle threader having means for mechanically positioning the plunger opposite the eye of the needle with a thread therebetween thus reducing eyestrain and time lost in positioning the device by eye; to provide such a needle threader composed of parts which can be economically made and assembled; to provide such a needle threader having an improved plunger for positively engaging the thread to pass the same through the needle's eye.

An illustrative embodiment of the invention is shown in the accompanying drawing, wherein:

Figure 1 is a fragmentary perspective view of certain parts of a sewing machine with my new needle threader applied thereto;

Figure 2 is a horizontal sectional view of the same taken on lines 2—2 of Figures 1 and 3;

Figure 3 is a vertical sectional view thereof taken on line 3—3 of Figure 2 and showing certain parts in different moved positions;

Figure 4 is an enlarged fragmentary central vertical sectional view of a portion of a needle including the needle's eye, thread, and the end of the plunger of the device in position for threading the needle, the section being taken on lines 4—4 of Figures 5 and 6;

Figure 5 is a horizontal sectional view of the same taken on lines 5—5 of Figures 4 and 6; and

Figure 6 is a fragmentary front elevational view of the lower end of a needle including the needle's eye, thread, and the plunger of the device in position for threading the needle.

Referring now in detail to these drawings wherein like parts are designated by the same numerals in the several views, the needle threader there shown has an elongated body comprising complementary body members 10 and 11 having two pairs of aligned, horizontal openings 12 therethrough and fastening means for securing said body members together comprising machine screws 13 passing through the pairs of openings 12 and provided with nuts 14 on the threaded ends thereof. Adjoining, complementary recesses

15 are formed in the body members 10 and 11 and are in communication with the openings 12 therethrough. A plunger 19 is reciprocably mounted in the body members 10 and 11 forming a horizontal cylindrical plunger bore 15, a vertical thread seat 16, a vertical needle seat 17 adjacent the thread seat 16 and conforming to the shape of a needle, and a rectangular stop seat 18 which intersects the plunger bore 15 medially thereof and at right angles thereto.

A plunger 19 is reciprocably mounted in the plunger bore 15 of the body, said plunger having a reduced forward end portion 20 extending through a reduced forward end portion 21 of the plunger bore, said end portions of the plunger and the bore being rectangular in cross-section and being vertically elongated to substantially correspond with the shape of a needle's eye. The upper side of the plunger is cut away along a portion thereof to form a channel 22 having shoulders 23 and 24 at its opposite ends adapted to contact a stop 25 which is disposed in the stop seat 18 and which extends into the channel 22 thus to limit the reciprocating movements of the plunger 19.

The rearward end portion of the plunger 19 extends to the exterior of the body and is provided with a head 26 on the extremity thereof. A coiled compression spring 27 circumscribes the rearward end portion of the plunger 19 and is interposed between the plunger's head 26 and the body of the device, and said spring serves to normally urge the plunger in a rearwardly direction away from the thread seat 16 so that the reduced forward end portion 20 of the plunger normally lies rearwardly of said thread seat.

The needle threader is adapted to be applied to a sewing machine 28 shown fragmentarily in Figure 1 which has a clamp 29 for retaining the upper end of a needle 30 in such a manner that the measured distance from the clamp 29 to the needle's eye 31 is constant. The measured distance from the plunger 19 to the top of the body of the needle threader is equal to said distance from the clamp 29 to the needle's eye 31, and the threader may by this means be mechanically positioned with the needle's eye in alignment with the plunger and with a thread 32 positioned therebetween in the thread seat 16.

The forward extremity of the plunger's reduced end portion 20 is bifurcated as best illustrated in Figures 4, 5 and 6. One prong 33 of the bifurcation extends in an upwardly and outwardly direction while the other prong 34 of the bifurcation extends in a downwardly and oppositely outwardly direction. The plunger's extremity is thus positively adapted to engage the thread 32 and to pass the thread through the

needle's eye when the device is properly positioned and the plunger is manually pressed in a forwardly direction.

The needle threader as herein shown and described is a device separate from a sewing machine, but the invention comprehends modification of the device so that it can be pivotally or otherwise mounted on a sewing machine and thus incorporated in such machines at the time of their manufacture. While but one specific embodiment of the invention has been herein shown and described, it will be understood that the device may be modified without departing from the spirit of the invention as the same is defined by the following claims.

I claim:

1. In a needle threader, a body having a horizontal plunger bore, a vertical thread seat, and a vertical needle seat for seating a needle with the eye thereof in alignment with said plunger bore with a thread therebetween, and a plunger reciprocally mounted in the plunger bore and having an end portion adapted to engage said thread and pass the same through the needle's eye, said end portion of the plunger being bifurcated to form a thread-engaging notch, one prong of the bifurcation extending in an upwardly and outwardly direction, and the other prong of said bifurcation extending in a downwardly and oppositely outwardly direction.

2. In a needle threader, in combination with a needle having an eye near the point and a clamp for retaining the other end of the needle and maintaining said needle in a vertical position pointing downward, a body having a horizontal plunger bore, a vertical needle seat, and a vertical thread seat adjacent the needle seat and extending between the needle seat and said plunger bore, measured stop means on the body adapted to engage said clamp for aligning the

needle's eye with the plunger bore and with a thread in the thread seat, and a plunger reciprocally mounted in the plunger bore and having an end portion adapted to engage said thread and pass the same through the needle's eye, said end portion of the plunger being bifurcated to form a thread-engaging notch, one prong of the bifurcation extending in an upwardly and outwardly direction, and the other prong of said bifurcation extending in a downwardly and oppositely outwardly direction.

3. In a needle threader, a body having a horizontal plunger bore, a vertical thread seat, and a vertical needle seat for seating a needle with the eye thereof in alignment with said plunger bore and with a thread therebetween, and a plunger reciprocally mounted in the plunger bore and having an end portion adapted to engage said thread and pass the same through the needle's eye, said end portion of the plunger having a greater vertical dimension than horizontal dimension and being bifurcated to form vertically spaced prongs, said prongs being oppositely laterally bent to engage therebetween a vertical thread.

JOHN N. JAMO.
